UNITED STATES PATENT OFFICE.

PHILO SCOTT, OF FINE, NEW YORK.

EXCAVATING-TOOL.

No. 892,090.

Specification of Letters Patent. Patented June 30, 1908.

Application filed November 4, 1907. Serial No. 400,528.

To all whom it may concern:

Be it known that I, PHILO SCOTT, a citizen of the United States, residing at Fine, in the county of St. Lawrence and State of New York, have invented certain new and useful Improvements in Excavating-Tools, of which the following is a specification.

This invention relates to improvements in tools, designed for use in connection with earth excavation, grubbing or ditching, and the invention relates particularly to manually operated excavating tools, such as picks, mattocks and the like.

The object of the invention is to provide excavating tools which are simple in construction, durable and inexpensive, and whereby the work of digging or excavating may be done more quickly and requiring less manual power for their effectual operation than the old style or make of tools of the class.

The several features and parts of the invention will be readily understood from the detail description which follows, reference being had to the accompanying drawings forming a part of this specification, in which—

Figure 1 is a side elevation of a pick. Fig. 2 is a plan view of the inner face of the same. Fig. 3 is a plan view of the back of a pick. Fig. 4 is a cross-section of one of the blades or arms of a pick, taken on the line $a-a$ of Fig. 2 showing the triangular form of said blades. Fig. 5 is a plan view of a modified form of tool, showing one narrow, triangular and one broad semicircular blade. Fig. 6 is a sectional view, substantially on the line $x-x$ of Fig. 5.

Similar reference numbers designate like parts throughout the several views.

In the drawings, 2 represents the metallic portion of my improved tool, and 3 represents the narrow blades which are preferably formed triangular, as shown in Figs. 1, 2, 4 and 5. The object in providing the blades in the angular form shown, which resembles the old fashioned bayonet used by the military, is to add greater strength to the arms or blades of the tool than if they were formed square or flat as formerly made, and furthermore, it has been found that a blade formed as shown herein, is capable of being forced or driven into the earth to a greater depth and with the expenditure of less force or power, because of its peculiar shape, than any other form of such tool. After a pick or other tool having my triangular blade is sunk into the

earth by the workman, and he pries by means of the leverage afforded by the handle 7, the sharp inner edge or ridge 4 cuts its way through the earth readily and with little friction, and the angular sides or faces of the blade effect the loosening of a large section of earth or clay to be removed. By this means a larger amount of excavating may be accomplished in the same or less time than by the use of the old style of digging tools. 5 represents the central portion of the tools shown in Figs. 1, 2, 3 and 5 in which the handle 7 is fitted, an oval-shaped eye 8 being provided for the purpose. The point 6 of the blades 3 are preferably beveled, chisel-like, as shown in the drawings, so that they may cut their way into or through the earth more readily.

In Fig. 5 I have illustrated a modified form of excavating tool, in which the same general construction shown in the former figures is followed in all parts, except one blade 9, which is formed much broader than blades 3, and its outer end is made semicircular, the cutting edge or point thereof having a bevel 10, which gives it substantially the form of a half-round chisel or gouge. This blade 9 is for use in grubbing or in smoothing or leveling the bottoms of cellars, or trenches. In finishing trenches in which drain-pipe is to be laid the blade 9 is used for rounding the bottom so as to conform to the shape of the piping. In case of grubbing I find that the blade 9 will cut through roots of considerable size more readily than the old form of pick-axes or grub-hoes.

It is obvious that the principles of my improvement may be applied to other forms of excavating tools than those described and shown herein, and still be within the scope defined by the appending claims.

Having thus described my invention what I claim as new and desire to secure by Letters Patent is—

1. A tool of the class described, comprising a metallic body having a central eye or opening to receive a handle, a pair of oppositely arranged blades having three substantially equal sides formed with said body, the said sides being disposed in such manner that the outer face or back of each blade is flat, the inner face of each blade having a sharp central ridge, and the outer ends or points of said blades being beveled to form a cutting edge, substantially as described.

2. A tool of the class described, comprising a metallic body having triangularly formed

blades projecting in opposite directions therefrom and disposed so that the outer face of each blade is flat and the inner face or side thereof is formed with a sharp central ridge, the outer end of each blade being beveled, and an oval-shaped eye in the center of said body adapted to receive a handle, substantially as described.

3. A tool of the class described, comprising
10 a metallic body in combination with an operating handle, a pair of triangularly formed

blades projecting in opposite directions from said body and having their points or outer ends beveled inwardly toward said handle, substantially as described.

15

In testimony whereof I affix my signature in presence of two witnesses.

PHILO SCOTT.
